CARL I. JACOBSON AND ALFRED L. FOWLER, OF LOS ANGELES, CALIFORNIA.

CUSHIONING DEVICE.

1,133,203.

Specification of Letters Patent. Patented May 16, 1916.

Application filed March 14, 1914. Serial No. 824,714.

To all whom it may concern:

Be it known that we, CARL I. JACOBSON, a subject of the King of Norway, and ALFRED L. FOWLER, a citizen of the United States, residing at Los Angeles, in the county of Los Angeles and State of California, have jointly invented new and useful Improvements in Cushioning Devices, of which the following is a specification.

This invention relates to cushioning devices whereby shock or jar incident to sudden or violent movement, resultant upon jar or blow, may be neutralized; and the invention has for its object to provide such an improved cushioning device which will be adaptable to a wide range of uses and service in connection with a wide range of apparatus, mechanism and devices to which it may be applied for use or with which it may be associated.

The invention has for further objects the provision of such a cushioning device which not only will neutralize the jar or shock incident to first movement but will likewise cushion the jar or shock incident to the movement of reaction or the return movement. Cushioning devices as previously devised have aimed merely to correct the disturbances incident to the initial resultant movement, and have failed to neutralize or offset or counteract the disturbances resulting from the return or reaction movement.

The invention is particularly adapted for use in connection with vehicles such as automobiles, and provides an effective support for vehicle bodies, in which capacity it likewise performs its function of a cushioning device. The adaptability of the invention, however, to many other purposes, will be manifest from consideration of its broad and general aspects of utility.

In practising the invention we utilize two cushioning means or media, such as a spring or springs and compressed air, the action of one of which is more immediately responsive to disturbed conditions and the action of the other of which is subsequently effective and completes the cushioning. The compression of the air is automatically produced and the cushion of compressed air is automatically dissipated after it has been utilized; and the spring preferably constitutes the normally effective cushioning agency.

With the above and other objects in view, the invention consists in the novel and use-

ful provision, formation, construction, combination, association and relative arrangement of parts, members and features, all as hereinafter described, shown in the drawing 60 and finally pointed out in claims.

In the drawing: Figure 1 is a perspective view of a portion of an automobile body and rear construction illustrating the invention as applied thereto both as a body support 65 and cushioning device; and, Fig. 2 is an enlarged fragmentary sectional view of a portion of the vehicle showing the cushioning device more in detail, the rear axle of the vehicle being shown as disposed directly beneath the cushioning device, whereas the latter serves as a directly applied and acting support as well as cushioning device.

Corresponding parts in both figures are designated by the same reference characters.

Referring with particularity to the drawing, the improved cushioning device therein shown comprises, in the specific construction and organization represented, a piston 80 A which has a working fit within a cylinder B, the piston adapted to be connected, as by the piston or connecting rod 3 with the vehicle axle 4, either directly, as shown in Fig. 2, or through the medium of a lever 85 arm or the like 5 with which at one end the piston rod 3 is connected, such lever arm being intermediately fulcrumed as at 6, and having its other end pivotally connected with the frame 7 of the vehicle, by a pivoted 90 carrying plate 8. This statement is made with respect to the application of the cushioning device as a vehicle body support; and it is to be understood that the piston rod 3 may be connected with any suitable support or device; the cylinder B likewise being connected with any other suitable device or thing, being shown in the drawing as connected with the vehicle body 7. The piston in its travel within the cylinder is 100 adapted to play over two ports or series of ports, 9 and 10, formed each in only one zone in the walls of the cylinder and spaced apart, the normal position of the piston being between said ports or series of ports: 105 and said piston in its travel being adapted to cover either one or the other of said ports or series thereof. Between the piston and the vehicle body section or other device, is interposed a coil compression spring 11. 110 Specifically this is shown as housed within the crown 12 upon the upper end of the

- cylinder B, and which is threaded to receive an adjusting screw plug 13 whereby the normal condition of the compression of the spring may be varied. A stud or post 14 rising from the piston is accommodated within the coils of the spring 11 and keeps the same centered upon the piston; such stud and the crown 12 preventing the spring from collapsing or being distorted.
- 10 In the drawing the cylinder B is shown as bolted to the body 7, the crown 12 being passed upwardly through a suitable opening in the bottom of the body and a flange 15 upon the cylinder abutting against the bottom of the body and being bolted thereto as at 16.

It will be understood that with the use of the lever 5 shown applied to the rear axle 4 and connecting the piston rod 3 with the 20 supporting plate 8, in pivotal couple, the degree of play of the piston within the cylinder may be regulated, and the dimensions or gage of the spring 11 varied in accordance with the length of the lever 5 at each 25 side of its fulcrum. In other words, the closer the fulcrum 6 approaches the supporting plate 8, which is linked to the piston, the greater will the play on the piston be for any given disturbance and therefore the 30 greater the resultant compression action of the spring, so that a spring of greater length but less gage stock may be substituted at each step of approach of the fulcrum 6 toward the supporting plate 8. In its broad 35 aspects, however, the invention is not concerned specifically in application to road vehicles, in which it will be noted from the above description and drawing that it serves both as a body support and a cushioning device; but the invention is adapted to a wide 40 range of uses in connection with counter-acting disturbances of stability of many sorts.

In its specific action, the cushioning device 45 involves the joint action of the piston A upon the air imprisoned in either end of the cylinder and of the spring. Or, the cushioning action of the spring and compressed air may be applied upon movement 50 of the piston in only one direction, and the cushioning action of compressed air may be solely depended upon in the movement of the piston in the other direction, as indicated in the full-line showing in the drawing. However, the spring 11 may be duplicated at the other side of the piston A, as 55 indicated in dotted lines, whereupon there will be a resisting action of both spring and compressed air in the movement of the piston in each direction, so that both the initial and reactive movements or rebound movements due to disturbance of stability will be counter-acted or opposed or neutralized by both spring action and compressed air action.

When the piston A has traveled sufficiently, responsive to a disturbance such as the jar imparted by the passage of the vehicle over obstacles in the roadway so that the piston has closed and passed one of the 70 ports or series of ports 9, compression of the air imprisoned by the piston in the respective end of the cylinder at once takes place. Prior to such compression, the jar or shock is counter-acted by the spring alone; but 75 when such compression commences the resultant air cushion acts in an auxiliary capacity and supplements the spring action. Immediately upon complete counter-acting 80 of the disturbance to the extent that the initial piston travel has been terminated, a reaction or rebound will be effected, due to the compression of the spring and of the air. The piston will therefore execute a return movement, passing the port 9 or 10 and 85 allowing the air cushion behind the piston to be dissipated, and will close and pass the other port 9 or 10 imprisoning the air at the corresponding end of the cylinder and producing a reactive cushioning action similar 90 to that first set up, supplemented by the cushioning action of the spring 11 if it be deflected to that end of the cylinder. This second cushioning or curbing action will be followed by such further alternately opposite movements of the piston and the accompanying counter-balancing and cushioning actions as may be necessary to finally 95 and completely correct the disturbances originally set up; whereupon the piston will 100 have assumed its normal position intermediate of the ports 9 and 10. The final correcting or cushioning action will ordinarily be caused by slight flexion of the spring or 105 springs 11 without any participation of the piston in air compression.

It is manifest that many variations and substitutions may be made in adapting the invention to different conditions of use and service, all without departing from a fair 110 interpretation of the invention.

Having thus disclosed our invention, we claim and desire to secure by Letters Patent:

1. A cushioning device, comprising a cylinder, a piston within the cylinder, and a spring always opposing movement of the piston in the cylinder in one direction; there being spaced ports in only two zones in the cylinder for admission of air thereto for compression by the piston at opposite ends of the cylinder in the movements of the piston in opposite directions; said ports being controlled by movements of the piston; said piston being normally disposed between said ports.

2. A cushioning device, comprising a cylinder, a piston within the cylinder, and a spring always opposing movement of the piston in the cylinder in one direction; there being spaced ports in only two zones in the

cylinder for admission of air thereto for compression by the piston at opposite ends of the cylinder and controlled by movements of the piston; the normal position of said piston being between said ports and one of said ports being always open.

In testimony whereof, we have signed our

names to this specification in the presence of two subscribing witnesses.

CARL I. JACOBSON.

ALFRED L. FOWLER.
